UNITED STATES PATENT OFFICE.

WILLIAM S. GUTHRIE, OF DETROIT, MICHIGAN.

CARBURETER.

1,207,029.

Specification of Letters Patent. Patented Dec. 5, 1916.

Application filed April 3, 1914. Serial No. 829,181.

To all whom it may concern:

Be it known that I, WILLIAM S. GUTHRIE, a citizen of the United States, and a resident of Detroit, in the county of Wayne and State of Michigan, have invented a new and Improved Carbureter, of which the following is a specification.

My invention relates to carbureters for internal combustion engines, and the primary object of my invention is to provide a carbureter in which efficient mixtures are produced for a reasonable range of speeds when once properly adjusted to the engine.

The object of my invention is accomplished by a carbureter having a mixing chamber, primary and auxiliary fuel reservoirs, a fuel passage having a connection with each of the reservoirs, means whereby the liquid flows from said primary reservoir into said fuel passage in varying quantities during the operation of the carbureter, means adapted to discharge fuel into the mixing chamber from said fuel passage so that the said discharge includes the liquid contents of the auxiliary reservoirs, and means whereby fuel is supplied from the auxiliary reservoir when the engine is normally running at a low rate of speed.

One feature of my invention consists in the combination of a mixing chamber, a main fuel feeding device communicating therewith, and a second fuel feeding device adapted to supply fuel when the engine is normally running at a low rate of speed, which second fuel feeding device ceases to discharge fuel when the engine is running at higher speeds, and compensates the fuel supply by admitting air to the main fuel feeding device.

The invention further consists in the details of construction shown, described and particularly pointed out in the claims.

In the accompanying drawings Figures 1, 2, 3 and 4 are central vertical cross sections of four modifications of a carbureter embodying the present invention, said carbureter being of the vertical type. Figs. 5 and 6 are longitudinal sections of fuel nozzles.

Fig. 7 is a longitudinal section through another carbureter of the vertical type. Figs. 8 and 9 are corresponding sections of two modifications of carbureters in each of which the mixing chamber is horizontal. Fig. 10 is a section on the line 10—10 of Fig. 8.

Fig. 11 is a section on the line 11—11 of 55 Fig. 9.

Similar reference characters refer to like parts throughout the several views.

The main fuel reservoir 1, of all the modifications shown in the drawings, is provided with a top 2, having an inlet connection 3 and air vent 4. A float 5 has a stem 6, provided with a valve 7 at its upper end and guided at its lower end. Any other means may be employed to supply the liquid fuel 60 to the main fuel channel or passage.

The mixing chamber 9 of the different constructions has an air inlet 10, mixture outlet 11, a Venturi tube 12, a transverse shaft 13, a throttle valve 14 on the shaft, and a main fuel feeding device, or nozzle 15. When the engine is normally running at the lowest speed this throttle valve is preferably set slightly open to permit a slight flow of air as shown in Fig. 1. This nozzle may 70 have a single discharge opening 16 at its upper end, as shown in Figs. 1 to 4, and 7 to 11, it may have a plurality of discharge openings 17, as shown in Fig. 5, or it may be open ended and be in the form of a tube 18, 75 having a restriction near the lower end as shown in Fig. 6 or the restriction may be nearer the top of the tube if desired. The various modified forms of this invention operate in substantially the same way, but each 80 differs slightly from the others in construction, as will be hereinafter explained.

In each carbureter shown in the drawings, is provided a main fuel channel or passage to which fuel is supplied in varying quantities from a main source of fuel supply and an auxiliary reservoir is also provided, in which liquid fuel is temporarily stored, and from which reservoir fuel is supplied to the engine when running at low speeds, that is, 90 with the throttle nearly closed. When the throttle is opened a predetermined distance any fuel which is in such auxiliary reservoir will flow through the said fuel passage and be discharged into the mixing chamber 9 100 through the jet 16 of the nozzle 15, because the jet 16 is capable of discharging the fuel at a faster rate than the connection with the main reservoir 1 permits it to flow into the said fuel passage. The jet 16 may be controlled by a regulating needle valve when 105 desired. The constructions of the parts constituting the auxiliary reservoir and the fuel

passages differ in the several constructions shown in the drawings.

The air flows to the mixing chamber 9 and also to the auxiliary reservoir from the 5 inlet passage 10, and by this means less air will flow to the auxiliary reservoir at high speed than at low speed, because at high speed a partial vacuum is formed in the passage 10. Thus the air pressure in the 10 auxiliary reservoir will be lower at high speed, and the flow of the air from the auxiliary reservoir into the fuel passage will therefore vary with the speed of the engine. The auxiliary reservoirs may be opened to 15 the atmosphere if desired.

In the carbureter shown in Fig. 1, an auxiliary reservoir 20 connects to the mixing chamber 9 by means of a small passage 21. A pipe 22 extends down from the plug 23 20 into the well 24 mounted in the screw-plug 25. The well extends up above the level of the liquid fuel in the chamber 1, and the pipe 22 extends below such level. A calibrated orifice 26 in the plug 25 discharges 25 fuel into the auxiliary reservoir 20 when the engine is running slowly and the throttle is nearly closed.

An opening 27 permits the fuel to flow into the reservoir 20, and a calibrated orifice 28 in the bottom of the well 24 determines the flow of fuel from the auxiliary reservoir 20 into the said well for the low speed of the engine. Passages 29 and 30 permit communication between the air inlet 30 passage 10 and the reservoir 20. An auxiliary passage 31 is controlled by the valve 32 having a crank arm 33 so that the valve may be opened from a distance when a greater supply of fuel is desired than 35 normally flows from the calibrated opening 34 into the passage 36. The opening 34 usually has a greater capacity than the orifice 26, and usually has less capacity than the orifice 16, that is, the opening or openings 40 in the nozzle 15, when subjected to a strong suction, are of greater discharge capacity than the orifice 34, even when the area of the orifice 34 is somewhat larger than the discharge opening or openings in 45 the nozzle 15.

Air normally passes through the inlet 10 up around the nozzle 15 and through the outlet 11 to the engine, the flow being controlled by the valve 14. Some of the air 55 that enters at 10 flows through the passages 29 in the lower end of the Venturi tube and through the opening 30 into the reservoir 20, thence down into the well 24, up the pipe 22 and through the passage 21 60 into the mixing chamber 9 above the throttle 14. When the auxiliary reservoir is empty some of the air that enters the same flows down around the well 24 and through the orifices 27 and 26, into the fuel passage 36, 65 where it mixes with the fuel and flowing

up through the nozzle 15 is discharged into the mixing chamber 9.

Part of the air that flows down through the opening 27 will pass up through the orifice 28 into the well 24 and also up the tube 22. After the fluid once enters the well 24 through the orifice 28 it does not reverse in its direction of travel provided the air pressure in the well 24 is lower than it is in the auxiliary reservoir 20 which will be 70 the case if the orifice 28 feeds the oil under the influence of suction. The air pressure in this reservoir, as in the auxiliary reservoirs shown in Figs. 4, 7, 8 and 9, is atmospheric when the engine is normally running 75 at a low rate of speed. The well 24 may be used in addition to the auxiliary reservoir shown in any of these figures when it is desired to get a more perfect adjustment. 80

By employing the well 24 in addition to the auxiliary reservoirs shown in the above figures it is possible to make a very fine adjustment of the carbureter for any motor, as the compensating jet 26 may be of such size as will permit entrance of air to the 85 fuel passage in proper proportion without effecting the supply of fuel for the low speed, which is controlled by the jet 28 and which jet supplies fuel at a less rate than the compensating jet 26 supplies the same 90 to the reservoir 20. Some motors may however be fitted without using the well 24. The fuel flows up into the auxiliary reservoir 20 only when the engine is stopped or when it is running at a low rate of speed 95 with the throttle nearly closed, and at which time the suction at the jet 16 may be insufficient to draw the full supply of the fuel from the nozzle 15. 100

When the throttle is nearly closed, a very rich mixture of fuel will be drawn up from the well 24, through the pipe 22 and through the passage 21 into the chamber 9 above the throttle, where it mixes with the air that passes up around the throttle valve. This 105 constitutes the fuel supply of the engine when normally running at the lowest speed. 110

If the throttle is opened to approximately the position shown in Fig. 2, air will flow more freely through the Venturi tube 12 and the nozzle 15 will discharge fuel in addition to that which passes up the pipe 22. When the throttle is fully opened, a greater suction occurs at the discharge opening 16 because of the restriction at the lower end 115 of the Venturi tube 12, and at this time the opening 16 is capable of a greater discharge than the orifice 34, which will cause the fuel in the auxiliary reservoir to be drawn down through the orifice 26 into the fuel passage 12 36, and be discharged into the mixing chamber 9 together with the fuel from the orifice 34. This stops the liquid from flowing into the well 24, and air alone will pass up the pipe 22 and through the passage 21. 130

During the time the fuel in the auxiliary chamber flows from the opening 16, an abnormally rich mixture is being supplied to the engine, tending to cause an acceleration 5 of speed. As the speed increases, the mixture becomes leaner through the supply from the auxiliary reservoir ceasing, and the sole supply coming from the orifice 34, which is of less discharge capacity than the opening 10 16. Air will now pass down around the well 20, through the opening 27, and the calibrated orifice 26, and mix with the fuel in the fuel passage 36, and pass into the mixing chamber through the jet 16, thus causing the 15 mixture to be of the proper leanness, the orifice 26 being calibrated to insure such a mixture. Thus it will be seen that the orifice 26 constitutes a compensator that supplies fuel for the low speed of the engine and 20 at higher speed it acts as a vent for the suction controlled jet 16.

Under certain conditions, an additional supply of fuel may be desirable. This can be furnished by opening the needle valve 32 25 by means of the crank arm 33 to permit fuel to flow through the passage 31 to the main fuel passage 36. This is especially of value during cold weather when an additional amount of fuel is necessary to run the engine 30 with reasonable power while being warmed up. The float chamber may be drained by removing the plug 38. Liquid fuel is temporarily stored in the space below the plug 26 and this liquid is discharged by the jet 16 in 35 like manner with the liquid stored in the auxiliary reservoir. The volume may be varied by increasing or decreasing the length of the plug 26. The rate of flow of fuel through the passage 21 may be varied by 40 the needle valve 37, provided the fuel is drawn through the orifice 28 by suction, which may be accomplished by restricting the air inlet to the well 24. By removing the well from the plug 25, it is obvious that 45 the oil in its raw state (without air) will be drawn up the tube 22 at the lowest speed, since the orifice 26 is capable of supplying the oil at a faster rate than then required, and since the intake end of the tube 22 is below 50 the normal level of the liquid in the float chamber.

In Fig. 2 the compensating jet 42 in the plug 41 is substantially at the bottom of the auxiliary reservoir 43. The flow of fuel and 55 air through this jet 42 is substantially the same as it is through the jet 26 in Fig. 1 previously described. The pipe 44 does not extend down into the fuel when the engine is stopped, but a slight vacuum due to restricting 60 the air through the opening 30 will cause the fuel to rise to the lower end of the pipe, up which it will be drawn with some air and discharge into the mixing chamber 9 above the throttle valve. As in the other views, the 65 lower end of this pipe is beveled, which tends

to mix the air and liquid as it enters the pipe. The fuel passage 36 is in this modification connected to the fuel chamber 1 by means of a plug 36^a having an orifice 34^a therein corresponding to the opening 34 heretofore described. The needle valve 45 may be turned back to admit air through the passage 46, thereby reducing the suction and flow of fuel. This construction is very convenient for varying the fuel supply for the engine 75 when running at low speed. This passage 46 may be calibrated when the carbureter is to be used on only one type and size of engine, in which case the valve 45 may be omitted. 80

The carbureter shown in Fig. 3 has an auxiliary reservoir 48 in the form of a removable tube having a restricted opening 49 in its upper end, above the level of the fuel in the reservoir 1, its lower end having 85 unrestricted communication with the fuel passage at 50. In the operation of the engine when normally running at the lowest speed, air passes from the inlet 10 through the opening 51 around the upper end of 90 the reservoir 48 into the chamber 52 and finally into the outlet 11 through the passage 53. Fuel may then be drawn by suction through the jet 49 from the auxiliary reservoir 48 when the engine is normally 95 running at the lowest speed provided the opening 51 is sufficiently small to cause a slight sub-atmospheric pressure in the chamber 52. If the throttle is opened sufficiently the air pressure in the chamber 9 will 100 naturally fall below that in the chamber 52 and the jet 49 will cease discharging fuel because the jet 16 is now capable of a greater discharge than the orifice 54 in the valve 55, which supplies the fuel from the 105 main reservoir 1. The jet 49 will now admit air into the reservoir 48 from the chamber 52 which permits the fuel in the reservoir 48 to be drawn downwardly into the passage 36 to supplement the supply that is received directly from the reservoir 1. Air will follow the liquid into the fuel passage 36 from the reservoir 48, which compensates the fuel supply as before described. The 110 valve 55 may be adjusted in respect to its seat by the lever 56 and threads 57 to afford an additional supply of fuel if desired. 115

In Fig. 4, the reservoir 61 extends up into the chamber 62 which communicates with the air inlet 10 by means of the opening 63. For adjusting the low speed fuel supply the pipe 65 is mounted in a threaded bushing 64 so that it can be removed and another substituted of a different length. The lower the pipe extends into the liquid the greater will be the flow of the liquid for the low speed. If, however, the orifice 69 is so large that the oil flows therethrough too freely for the low speed, then this method of varying the oil supply will be of no use; 120 125 130

but the oil for the low speed may then be regulated by calibrating the passage 71, or this passage 71 may be controlled as by the valves 37 and 45 shown in Figs. 1 and 2, respectively. In the latter operation of the auxiliary feeding device it will be seen that the oil in its raw state (without air) will be drawn up the tube 65 when the engine is normally running at the lowest speed, and at which time the air pressure in the auxiliary reservoir 61 will be atmospheric. This operation may be had with all the carbureters shown in the drawings except those shown in Figs. 2 and 3.

When the throttle is nearly closed, fuel will flow through the calibrated orifice 66 in the spring held valve 67 into the fuel passage 68 and up through the compensating jet 69 in the plug 70 into the reservoir 61 and up the pipe 65 to the mixing chamber at 71. Air from the chamber 62 flows down into the reservoir 61, to the lower end of the pipe 65, and passing up, enters the mixing chamber through the passage 71. When the throttle is opened a certain distance the flow of fuel through the compensating jet 69 will reverse as heretofore described.

The lower end of the stem 6 of the float 30 may be guided in the upper end of the drain cock 73, which is provided to drain the main reservoir 1. The valve 67 may be held against its seat by the spring 74, but by pulling on the stem 75 of this valve a greatly increased flow of fuel is obtained for starting the engine without disturbing the normal adjustment of the other parts of the carburetor.

The carburetor shown in Fig. 7 is formed with a horizontal outlet passage 11, which is sometimes desirable for attaching the same to engines requiring a horizontal connection. The body of this carburetor is made in two parts, 95 and 96, and a proper flange with a series of screws 97 provides suitable means for joining the two parts together, the upper end of the Venturi tube 12 being used to properly locate the said parts when assembling the same.

Air from the inlet 10 will flow up around the lower end of the Venturi tube 12 and through the opening 30 into the auxiliary reservoir 20 and down to the lower end of the tube 22 and discharge into the mixing chamber 9 through the passageway 21, which, as in all the other views, discharges into the said chamber 9 adjacent the throttle valve. This passageway 21 may be positioned at any point where it will be subjected to the suction in advance of the throttle.

The calibrated orifice 26 will supply the liquid to the reservoir 20 as fast as it is drawn out through the tube 22 for the low speed of the engine when the throttle is

nearly closed and when the throttle is opened sufficiently, the discharge from the jet 16 will include the liquid in the reservoir 20, it passing down through the compensating jet 26 into the fuel passage 36 and up the nozzle 15. Air will follow the liquid from the reservoir 20 into the fuel passage 36 which compensates the fuel supply for the higher speeds.

The carburetors shown in Figs. 8 to 11 have horizontal mixing chambers 9. This type is especially desirable where the carburetor is to be fastened directly to the engine casting without the necessity of the usual manifold. Air enters the air inlet 10 and flows through the mixing chamber 9 and out the passage 11 to the engine.

In Figs. 8 to 10 part of the air that enters at 10 will flow around the rear end of the Venturi tube 12 and into the reservoir 20 through the opening 30 and down to the lower end of the tube 22 up which it passes to the passage 76 from the openings 77 and through the duct 78 and passage 21 to the mixing chamber 9. The liquid is likewise supplied to the said mixing chamber through the passage 21 from the auxiliary reservoir 20 when the throttle is nearly closed and the engine is running slowly.

The calibrated orifice 26 supplies the liquid to the reservoir 20 as fast as it is drawn up the tube 22, as before described. At higher speeds this jet 26 compensates the fuel supply as also before described. The tube 22 is carried by the bushing 79 which is threaded at 80 and provided with a knurled button 81. This provides a convenient means for adjusting the supply of fuel for low speed, by raising or lowering the tube as required. If the compensating jet 26 be too large, other means as before described may be employed to regulate the auxiliary fuel supply. The nozzle 15 has its restricted discharge jet 16 slightly below its upper end which tends to deliver the fuel readily where the air flows horizontally past the said nozzle.

The air opening 87 in the lower side of the mixing chamber 9 prevents the chamber filling with the liquid should the nozzle overflow from any cause, and this opening serves another valuable purpose in this particular type of carburetor. When the engine is running at only a moderate speed the suction causes the jet 16 to discharge the liquid with but slight force and as the air passing through the Venturi tube is traveling at a comparative slow rate it may sometimes fail to properly vaporize the fuel and cause a loading up condition. If this loading up occurs, the engine will possibly miss firing. The opening 87 therefore tends to prevent a loading up from this cause, by admitting air to the mixing chamber at a position where the liquid may collect.

In the carbureters shown in Figs. 9 and 11 the fuel is conveyed to the mixing chamber from the auxiliary reservoir 20 for the low speed of the engine in the same manner 5 as shown and described in Figs. 8 and 10.

Air enters the passage 82 through the adjustable opening 83 and flows to the auxiliary reservoir 20, the amount of air being controlled by the screw 84 which is adapted 10 to close over the opening 83 for this purpose. After entering the auxiliary reservoir 20 the air passes up through the tube 22 to the mixing chamber as before described. The fuel is supplied to the reservoir 15 20 through the calibrated orifice 26 as fast as it is drawn up the tube 22 for the low speed and at high speeds this orifice 26 compensates the fuel supply by admitting air to the fuel passage 36 in the same manner 25 as before described. The tube 22 is mounted in a removable bushing 88 which makes it an easy matter to remove the same for the purpose before stated.

The liquid enters the fuel passage 36 25 through the orifice 34 in the plug 85 which being of tubular formation forms the fuel passage 36. The liquid passes freely through the openings 86 to and from the auxiliary reservoir 20, but the jet 26 restricts 30 the communication between the said reservoir 20 and the fuel passage 36.

The plug 85 may be removed easily so another can be substituted when fitting the same to an engine, as will be apparent. 35 The space below the nozzle 15 will be filled with the liquid and emptied in like manner with the reservoir 20 and the size of this space may be varied, depending on the length of the various plugs shown in the drawings. The discharge orifices in the nozzles 15 in all the carbureters shown, being unusually large, will discharge fuel under moderate suction; a Venturi tube of 40 reasonably large size may therefore be used to insure the maximum power of the engine. 45

The delivery of fuel from the orifice 16 50 may be slight until the throttle is opened to approximately the position shown in Fig. 2, and as the throttle opening is increased the suction becomes stronger and stronger and unless some compensating means were provided the jet 16 would discharge the liquid too freely beyond a certain speed. In Fig. 55 1 the fuel supply is compensated by arranging the jet 26 so that it permits the passage of air to the fuel passage 36 in proper proportions with the liquid that enters the fuel passage from the main source of the fuel supply through the restricted orifice 34, and from the time the air begins to enter through this orifice 26, no matter how much faster the speed may be it will properly compensate the fuel supply. This compensating jet 26 is made in the form of a bushing 60 and is held in position by screw threads as

shown, which makes it removable so that one of proper size of opening may readily be substituted to suit the particular engine on which the carbureter is used.

In each carbureter shown in the drawings 70 will be found a fuel feed jet that compensates the fuel supply in the same manner as the jet 26 just described. It will be noted that these compensating jets all permit the passage of the liquid for the lowest speed 75 of the engine when running under normal conditions, and at higher speeds these jets admit air, for the purpose of checking the suction on the restricted passageway that connects with the main supply reservoir; 80 and that the fuel supply through this restricted passageway varies with the speed of the engine.

The carbureters may all be provided with any of the usual means for limiting the air 85 supply in order to secure rich mixtures for starting the engine.

The modifications shown indicate that many other changes may be made in the construction of this carbureter without departing from the spirit of my invention as 90 set forth in the following claims.

I claim:

1. In a carbureter for internal combustion engines, in combination, a mixing chamber 95 having a fuel jet therein, a supply reservoir, a fuel passage having restricted connection with the supply reservoir and supplying fuel to said jet, an auxiliary fuel tube for conveying fuel to the mixing chamber, an auxiliary fuel container having restricted 100 connection with said fuel passage, an additional fuel container within said auxiliary fuel container, and from which additional fuel container the said auxiliary fuel tube 105 sucks, means for varying the air pressure in said auxiliary fuel container during the operation of the carbureter.

2. In a carbureter, a mixing chamber having a fuel opening communicating therewith, a main supply reservoir, a fuel passage having restricted connection with said supply reservoir and feeding said fuel opening, an auxiliary fuel reservoir having restricted connection with said fuel passage, 110 an auxiliary fuel passage for conveying fuel from said auxiliary reservoir to the mixing chamber, and means whereby the air pressure in said auxiliary reservoir is caused to vary from atmospheric to sub-atmospheric during the operation of the carbureter. 115 120

3. In a carbureter, the combination of a body having a mixing chamber therein, a throttle for controlling the flow of fluids 125 through said chamber, a main fuel feed passage, restricted means for supplying fuel to said fuel passage, an auxiliary reservoir having restricted connection with said fuel passage, means for discharging fuel from 130

said fuel passage into the mixing chamber, so that the said discharge includes initially liquid fuel and finally air from the auxiliary reservoir and means for discharging 5 fuel into said mixing chamber on the exit side of the throttle valve from the said auxiliary reservoir when the engine is normally running at a low rate of speed.

4. In a carbureter, the combination of a 10 body having a mixing chamber therein, a throttle for controlling the flow of fluids through said chamber, a main fuel passage, restricted means for supplying fuel to said passage, an auxiliary reservoir having restricted 15 connection with said passage, means whereby the fuel in the auxiliary reservoir may be discharged into the fuel passage, means for discharging fuel into said chamber from said passage so that the said discharge 20 includes initially liquid fuel and finally air from the said auxiliary reservoir, and means for discharging fuel from said auxiliary reservoir into said chamber in advance of said throttle, when the engine is 25 normally running at a low rate of speed.

5. In a carbureter for internal combustion engines, the combination of a body having an air inlet passage, a mixing chamber having connection with the air inlet passage, 30 a supply reservoir, a fuel passage having restricted connection with the supply reservoir, an additional reservoir having restricted connection with the fuel passage, means for supplying air to the additional 35 reservoir from the said air inlet passage, means for supplying liquid fuel from the additional reservoir when the engine is normally running at a low rate of speed, and means for discharging fuel into the mixing 40 chamber so that the said discharge includes initially liquid fuel and finally air from the said additional reservoir.

6. In a carbureter for internal combustion engines, the combination of a body having 45 an air inlet passage, a mixing chamber having restricted connection with the air inlet passage, a supply reservoir, a fuel passage having restricted connection with the supply reservoir, an additional reservoir having 50 restricted connection with the fuel passage, means for supplying air to the additional reservoir from the said air inlet pas-

sage, means for supplying liquid fuel from the additional reservoir when the engine is normally running at a low rate of speed, 55 and means for discharging fuel into the mixing chamber so that the said discharge includes initially liquid fuel and finally air from the said additional reservoir.

7. In a device of the character described, 60 a suction controlled fuel feed jet, an additional jet arranged in a plug and adapted to supply hydrocarbon fuel when the engine is normally running at a low rate of speed, and to admit air to the said suction controlled jet at a higher speed.

8. In a device of the character described, 65 a suction controlled fuel feed jet, an additional jet arranged to supply fuel when the engine is normally running at a low rate of speed, and to admit air to the said suction controlled jet at a higher speed, means for varying the size of the said additional jet.

9. In a carbureter comprising a body having a mixing chamber therein, a suction controlled fuel feed jet communicating with 70 said mixing chamber, an additional jet removably mounted and positioned so that it supplies hydrocarbon fuel when the engine is running at a low rate of speed, and to 80 admit air to the said suction controlled fuel feed jet at higher speed.

10. In a carbureter, a mixing chamber, a suction controlled fuel feed jet communicating with the said mixing chamber, an additional jet arranged so that it supplies fuel for certain low speeds of the engine, and to admit air to the said suction controlled fuel feed jet at higher speed, means for regulating 85 the said additional jet.

11. In a carbureter, a mixing chamber, a suction controlled fuel feed jet therein, a bushing substantially forming an additional jet that supplies hydrocarbon fuel for certain low engine speeds, and admits air to 90 the said suction controlled fuel feed jet at higher speeds of the engine.

In testimony whereof I have signed this specification in the presence of two subscribing witnesses.

WILLIAM S. GUTHRIE.
